UNITED STATES PATENT OFFICE.

J. HERON FOSTER, OF PITTSBURG, PENNSYLVANIA.

IMPROVEMENT IN ATTACHING TYPE TO CYLINDRICAL FORM-HOLDERS.

Specification forming part of Letters Patent No. 35,929, dated July 22, 1862.

To all whom it may concern:

Be it known that I, J. HERON FOSTER, of the city of Pittsburg, in the county of Allegheny and State of Pennsylvania, have invented a new and useful Improvement in Attaching Movable Type in Combination with a Curved Stereotype-Plate to a Detachable or Permanent Segment of a Cylinder, such as are used in rotating or oscillating printing-presses; and I do hereby declare that the following is a full, clear, and exact description thereof, reference being had to the accompanying drawings, which form part of this specification, and to the letters of reference marked thereon.

My invention relates to an improvement in that class of printing-presses in which the form is locked up upon a detachable or permanent segment of a continuous rotating or oscillating cylinder called by compositors a "turtle," which constitutes the bed or chase. In this class of printing-presses the form is either made up wholly of movable type and attached to the cylinder in that form, or a stereotype-cast is taken from the type so set up, which is curved to suit the periphery of the impression-cylinder and secured thereto in place of the movable type. Since the art of rapid stereotyping has been brought to such perfection this mode has been very generally adopted as a means of preventing the wear and tear of the type consequent upon the rapid working of the press; also, as a means of keeping the type clean, whereby a great saving is effected; but in the offices of daily newspapers where it is found necessary to produce a change of matter with but a momentary stoppage of the press it is obvious that if the whole form were stereotyped this could not be accomplished.

The object of my invention is to overcome this difficulty; and it consists in stereotyping all but the latest news-matter, while the columns in which it is desirable to make frequent changes are set up of movable type in the form with the stereotype-plate and the paper printed therefrom. This arrangement admits of the changes so necessary in a daily paper to be made expeditiously and with but little delay.

The second part of my invention consists in arranging the movable type on a curved surface, in combination with a curved stereotype-plate and segment of the impression-cylinder, so that the sides of the type shall remain parallel with each other, while the face or lettered portion of the type describes the same curve as that given to the stereotype-plate.

The third part of my invention consists in making that portion of the segment, bed, or chase of the impression-cylinder upon which it is intended the base of the type shall rest deeper than that part occupied by the stereotype-plate, not by gradually increasing the depth, but by deepening it suddenly, so as to form a step or wall against which the type can rest and be supported, and also for the purpose of securing the face of the type on a line with the stereotype-plate and for holding them to the same degree of curvature.

The fourth part of my invention consists in the use of column-rules in the form of the segment of a circle, having grooves on both sides describing the same curve, in combination with wedge-shaped "leads" having a tongue at each end corresponding in size with the aforesaid grooves and sliding therein, and are intended to be used for the purpose of better securing the movable type upon the cylindrical bed or chase.

To enable others skilled in the art to understand and use my invention, I will proceed to describe the accompanying drawings, in which—

Figure 1 represents an isometrical perspective view of my improvement as it appears when detached from the press. The chase or turtle C is curved to suit the periphery of the cylinder upon which it is intended to be secured, and of which it forms a part. Around the edges of this turtle, and secured to it by small screws *e e e e*, is a low wall, within which the movable type and stereotype-plate B B B are placed, the lettered surface only projecting above. Between the wall of the turtle and movable type strips of sheet-brass, A A, are interposed, (these are known as "slugs" and "side sticks,") which are forced up to the type by means of pinch-screws *s s s s*, passing through the aforesaid wall, which confine the movable type in a solid mass against the stereotype-plate B B B.

Fig. 2 represents a transverse vertical section of that end of the turtle upon which the movable type repose.

All the figures in the drawings are lettered, and similar letters indicate like parts on all the figures.

Fig. 3 represents a transverse vertical section of the same cut through the stereotype-plate B. The walls of the turtle are shown in this figure to be undercut, with a corresponding increase of width in the stereotype-plate.

This dovetailing of the plate with the wall insures its perfect security, as the pressure while at work is exerted only on the face.

Fig. 4 is a longitudinal vertical section of Fig. 1, and shows more particularly the position that the movable type occupy in relation to the stereotype-plate and curved surface of the turtle. The stereotype-plate B B B being comparatively thin, it is essential that it should rest upon a solid base to prevent disarrangement. To accomplish this and bring the face of the type on a line with the face of the plate, I have constructed the turtle with a channel or recess, D, in which the blank ends of the type rest, for the double purpose of compensating for the difference between the length of the type and thickness of the stereotype-plate; also, for creating a shoulder or inner wall, K, against which the type are supported and held, as hereinbefore stated. The inner wall, K, is slightly undercut, while the upper surface of the stereotype-plate projects forward sufficiently to produce a large plain shoulder, in connection with the inner wall, of the proper depth for the type to stand against. This enables me to set the type with their sides parallel with each other, while their face describes the degree of curvature given to the plate and obviates the necessity of a wedge-shaped column-rule, thought to be indispensable where movable type are set upon a cylindrical surface. The difference is plainly shown by the red lines starting from a supposed center of the cylinder upon which the turtle is to be carried, and indicate the shape and size of the wedge-shaped column-rule which would be necessary to fill up the space were this plan of mine not adopted.

Fig. 5 represents the appearance that the type would assume where their sides are kept parallel with each other, their base resting on the periphery of a cylinder less than the one which I employ, which is nine inches in diameter.

Fig. 6 represents a perspective view of a turtle or segment, C, similar to Fig. 1, and differing from it only in this respect, that the entire columns can be made up of movable type or used in connection with the stereotype-plate, if so desired; and for this purpose I have between each column of type a curved column-rule, R R R, having a projection at each end (indicated by the letters m m) fitting in a groove, p p, formed in the inside of the wall that surrounds the turtle C, Fig. 6. This retains the rules R R R in close proximity to the bottom of the turtle C, Fig. 6, and prevents their raising out of place when the press is in motion, while they can be adjusted sideways to accommodate the various-sized columns of type. On both sides of these curved column-rules are small narrow channels i i, running their entire length and of the same degree of curvature. As the forms are made up, I place between each line of type thin wedge shaped leads x x x. (Represented in

Fig. 9, which is a cross-section of Fig. 6.) Each of these leads has a tongue or projection on its ends, which slides in the channels cut in the rules, and are for the purpose of filling up the space between each line of type and binding them near the top or face, for the type not standing parallel with each other, they must be slightly separated at the top, no matter how tightly they are pressed together at their base; but by the use of my curved and grooved column-rule, in combination with the wedge-shaped leads and pinch-screws s s s, operating against the heavy slugs L L L at the end of each column, the type are as securely held on a curved surface as they can be on the old flat bed.

Fig. 7 represents a cross-section of Fig. 6, giving an end view of the curved column rules R R R R, with their grooves i i i on both sides and the leads L L supporting the type.

Fig. 8 represents one of my improved column-rules detached, and shows more particularly the projections at each end m m, the object of which was hereinbefore explained.

Having thus described my invention, I wish it distinctly understood that I lay no claim to the use of movable type upon a curved surface; neither do I claim a curved stereotype-plate, as these, separately considered, are old and well known; but

What I do claim is—

1. Using a stereotype-plate in combination with movable type on a curved surface by making that portion of the turtle or segment of a cylinder upon which the base of the type rests deeper than that part occupied by the stereotype-plate for the purpose of bringing the face of the type to the same degree of curvature, also for creating a wall or shoulder against which the type may be secured.

2. The use of column-rules in the form of the segment of a circle, having grooves on one or both sides describing the same curve, in combination with wedge-shaped leads or equivalent device, for the purpose hereinbefore stated.

3. Separating the upper portion or face of the lines of type (arranged for printing on a curved surface) to a greater distance than the base thereof by means of wedge-shaped leads or equivalent device without requiring the type to be grooved for the purpose of retaining them in place.

4. The use of a stereotype-plate formed in such a manner as that the face or lettered surface shall be longer and project over the lower edge of the bearing part next to the movable type when used upon a cylinder or curved surface sufficient to dispense with the use of wedge-shaped column-rules, which would be indispensable upon a curved surface if this were not done.
